UNITED STATES PATENT OFFICE.

JOSEPH V. HARTMAN AND ALBERT WETZEL, JR., OF LINWOOD, OHIO.

CAR-COUPING.

SPECIFICATION forming part of Letters Patent No. 288,797, dated November 20, 1883.

Application filed April 28, 1883. (No model.)

To all whom it may concern:

Be it known that we, JOSEPH V. HARTMAN and ALBERT WETZEL, Jr., both of Linwood, Hamilton county, Ohio, have jointly invented 5 a new and useful Improvement in Car-Couplings, of which the following is a specification.

In the accompanying drawings, Figure 1 shows (by side elevation of one and vertical section of the other) two draw-heads embodying our invention. These heads being of identical construction, the same description of parts is applicable to both. Fig. 2 shows a modification of the lifter-cam and spring.

A may represent a suitable draw-bar, and B 15 an attached "head," of any proper construction, having the customary open mouth or muzzle, b. C is a coupling-link; D, coupling-pin; E, sliding rest for coupling-pin; e, shank of same, whose head e' occupies a slot, a, in 20 bar A; F, spring to force said rest to the protracted position shown by dotted lines in the left-hand head. G is a lifter, whose shaft g,

extending to outside of draw-head, carries a cam, H, and a lever, I. A spring, J, pressing upon the cam H, operates to hold the lifter at 25 any position it may be placed.

Notches h may be provided in the periphery of the cam H, which, receiving a spur, j, on spring J, insure the retention of the lifter to any place of adjustment. 30

We claim as new and of our invention— The combination, with draw head and bar A B, link C, sliding rest E, and coupling-pin D, of the lifter G, having a cam, H, which receives the pressure of and is held by a spring, 35 J, as and for the purpose set forth.

In testimony of which invention we hereunto set our hands.

JOSEPH V. HARTMAN.
ALBERT WETZEL, JR.
